ASHTRAY

Kenneth Bashur, Aurora, Colo.

Application May 21, 1934, Serial No. 726,674

1 Claim. (Cl. 131—51)

This invention relates to improvements in ash trays.

In places where smoking is indulged in, it is essential to provide some convenient place for disposing of the ashes from cigars and cigarettes, because if this is not done, they will ultimately get on the floor and into the carpets, and cigar and cigarette ashes have always been found to be very difficult to remove.

10 I am aware that ash trays of different kinds have been invented and are in extensive use, but most of those with which I am familiar are merely open trays which are easily upset and when upset the contents are strewn over the 15 table or over the floor in a very objectionable way.

It is the object of this invention to produce an ash tray that shall be so constructed that it will have a pleasing appearance and will provide ample storage space for ashes.

Another object of the invention is to produce an ash tray that shall be so constructed that it will be difficult to upset, and if upset will prevent the ashes from being discharged on the 25 table or floor.

Another object of the invention is to produce an ash tray, the opening into which shall be provided with a wire or other open or perforated screen which serves as a support for cigars or 30 cigarettes and which can be employed for removing the accumulated ashes.

The above and other objects that may become apparent as this description proceeds are attained by means of a construction and an arrangement of parts that will now be described in detail, and for this purpose reference will be had to the accompanying drawing in which the preferred embodiment of the invention has been illustrated, and in which:

40 Fig. 1 is a top plan view of one of the improved ash trays which forms the subject of this invention;

Fig. 2 is a diametrical section taken on line 2—2, Fig. 1;

45 Fig. 3 is a section similar to that shown in Fig. 2, but shows a slightly modified construction; and

Fig. 4 is a diametrical section similar to that 50 shown in Fig. 2, but illustrating a still further modified form of the invention.

In the drawing reference numeral 5 indicates the bottom of the container whose vertical side wall has been designated by reference numeral 6. In the drawing, the container has been shown

as round and this is the preferable shape, but it may be a polygon, if desired.

The container is open at the top and the open end thereof is closed by means of a cover which is formed from a flange having a circular ring-like portion 7 provided with an inwardly extending flange 8. The flange 8 is located a short distance below the upper edge of the ring 7 and the lower portion of this ring telescopes over the upper edge of the wall 6, as shown clearly in Fig. 2. The opening in the cover is traversed by a wire mesh screen which is soldered or otherwise secured to flange 8. The wires of the screen have been indicated by reference numerals 9 and 10, and extend at right angles to each other as shown in Fig. 1. The openings between the wires are such that a cigarette can be introduced through these openings into the container. The upwardly extending edge of the ring 7 provides a flange about the opening in the cover and serves to prevent cigarettes from accidentally rolling off when laid on the screen. In Fig. 2, a cigarette has been indicated by dot and dash lines for the purpose of illustrating how they can be supported on the ash tray. The accumulated ashes on the end of the cigarette can be removed by brushing the end over the wire screen in an obvious manner. Since the ash tray is comparatively shallow, it stands firmly on its support and is very hard to turn over, and therefore there is very little danger of spilling the contents.

In Fig. 3, a slightly modified form has been shown in which the flange 8 extends inwardly a greater distance than in Fig. 2, so as to make the opening in the cover smaller. The opening is traversed by a wire screen similar to that shown in Figs. 1 and 2. The object of increasing the width of flange 8 is to offer greater obstruction to the ashes in case the ash tray is turned over on its side because the flange 8 will serve to hold the ashes in place even when there is a considerable accumulation.

In Fig. 4 a slightly modified form has been shown in which the bottom 5a is heavier than the corresponding part in the other figures. The side 6a is slightly curved and therefore if the ash tray is accidentally upset, the weight of the bottom will tend to roll it back into upright position. The cover is preferably cast and has a flange 7a whose outside diameter is the same as the outside diameter of the wall 6a. The lower portion of the flange, which has been designated as 7b, is offset inwardly so as to leave a rabbet for the reception of the upper end of

the wall 6a. With this construction, the outer surface of the ash tray is smooth to the top of the flange 7a. The cover has an inwardly extending flange 8a that terminates in a downwardly extending frusto-conical flange 11 that tapers inwardly and downwardly. The opening in the cover is closed by a wire screen like that shown in Figs. 1 and 2 and which is soldered or otherwise attached to the flange. Whenever ashes are rubbed off from the end of a cigar or cigarette, they fall through the wire screen and through the opening in the frusto-conical flange and fall into the container. In case this container is upset, the ashes will be prevented from falling out by the flanges 8a and 11. It is evident that an ash tray constructed like that shown in Fig. 4 can be turned upsidetown without spilling any of the ashes, because they will be held in place by the frusto conical flange.

It will be seen from the above that all of the modifications shown have this feature in common, that the container is provided with a readily removable cover having an opening that is traversed by a wire screen. This serves both as a support for cigars and cigarettes and also as a means for removing the ashes.

The container can be stamped from a piece of sheet metal and the cover portion can also be formed in the same way, but if desired the parts can be die-cast, in which case they can be made

heavier and provided with suitable ornaments on the outside.

The openings in the cover are of such size that cigarette butts, matches, etc., can be inserted through them and the container is therefore serviceable for other things than ashes. 5

Having described the invention what is claimed as new is:

An ash tray comprising, in combination, an open-top container with its open upper end defined by smooth, vertical walls, and a removable cover therefor, said cover comprising an upstanding flange conforming in outline with the upper end of said container and adapted to seat on and form a smooth continuation of the container walls, a second flange depending in integral, offset relation with said first flange and arranged to telescope within and frictionally engage against the container walls, an annular flange integral with and projecting in perpendicular relation inwardly from the aforementioned flanges adjacent the junction of the latter, a frusto-conical baffle forming an integral extension from the inner margin of said annular flange and disposed to open axially within said container below said flange, and a screen secured to and in the plane of said annular flange in traversing relation with the open base of said frusto-conical extension. 10 15 20 25
